UNITED STATES PATENT OFFICE.

ELWOOD HEADLEY, OF NEW YORK, N. Y., ASSIGNOR TO OSCAR B. FISH,
OF NEW YORK, N. Y.

DESIGN FOR A TOY SAFE-BANK.

No. 38,326.

Specification for Design.

Patented Nov. 27, 1906.

Application filed December 6, 1905. Serial No. 290,649. Term of patent 7 years.

To all whom it may concern:

Be it known that I, ELWOOD HEADLEY, a citizen of the United States, and a resident of the city of New York, county of New York, and State of New York, have invented a new, original, and ornamental Design for a Toy Safe-Bank, of which the following is a specification.

The figure is a perspective view of a toy bank, showing my new design.

I claim—
The ornamental design for a toy safe-bank, as shown.

ELWOOD HEADLEY.
